UNITED STATES PATENT OFFICE.

ROBERT ADAMS, OF LONDON, ENGLAND.

MEANS FOR LIFTING AND REGULATING TRANSOMS.

SPECIFICATION forming part of Letters Patent No. 661,838, dated November 13, 1900.

Application filed September 23, 1899. Serial No. 731,452. (No model.)

To all whom it may concern.

Be it known that I, ROBERT ADAMS, engineer, a subject of the Queen of Great Britain, residing at 67 Newington Causeway, London, England, have invented certain new and useful improvements in means or apparatus for lifting, regulating, and otherwise operating fan-lights and the like, also applicable for lifting and controlling other objects or articles, of which the following is a specification.

The object of my invention is to provide new or improved means or appliances for lifting, regulating, and otherwise operating fan-lights, swing-windows, cellar flaps or doors, and analogous articles, such means or apparatus being also suitable for other purposes where it is desired to propel or drive a rod, bar, plate, rope, cord, chain, or other attachment a required distance and so that such rod, bar, plate, rope, cord, or the like cannot move either way without being operated upon.

According to my invention I make use of a rack-and-pinion or pinion-and-gearing movement and provide the same with means whereby the motion thereof in either direction is automatically arrested on the operator removing his hand from the winder, key, knob, or other means for communicating motion to the pinion.

In order that my said invention may be particularly described and ascertained, reference is hereby made to the accompanying drawings, in which similar letters of reference indicate corresponding parts.

Figures 1, 2, and 3 illustrate a means for controlling the motion of the pinion by a pawl and cam-wheel. Figs. 4, 5, 6, and 7 illustrate a pawl locking device without a cam-wheel. Figs. 8, 9, 10, and 11 illustrate a means or sub-

40 stitute for the cam-wheel for disengaging the pawl. Figs. 12, 13, and 14 illustrate means for locking the pinion without a pawl.

Referring to Figs. 1, 2, and 3, *a* is a rack gearing with a pinion *b*, mounted within the case *c*.

45 *d* is a pawl pivoted at *d*⁴, engaging with the teeth of the pinion, *d'* being a stud, pin, roller, or other projection in contact with the edge of the cam-wheel *e*, which is also mounted in

50 the case *c*, but capable of partial rotation independently of the pinion *b*.

f is a spring or spring-pawl arranged to act as a brake or check on the cam-wheel *e*.

The pinion and cam-wheel are each formed with a socket, as shown, that of the cam-wheel being shaped to fit the shank of a key, winder, or other motion-transmitter and that of the pinion being irregularly shaped to allow of a partial rotation of the shank therein. Thus in Fig. 1 the shank if turned to the left would first communicate motion to the cam-wheel *e* and afterward to the pinion as well, as shown in Fig. 2. The boss of the cam-wheel is sunk within the pinion, as shown in Fig. 3, in which it is capable of a partial rotation, the external bosses or journals of the pinion and cam-wheel acting as pivots working in bearings in the case *c*. The pinion and cam-wheel are arranged so that on a suitable key, winder, or other appliance being inserted and turned in one direction the pinion and cam-wheel are free to rotate as an ordinary ratchet-wheel; but on being turned the reverse way the key or the like causes the cam-wheel to partially rotate and raise the pin *d'*, thus throwing the pawl *d* out of gear with the teeth. When the hand is removed from the motion-transmitter, (or when the key or the like is withdrawn,) the pinion partially rotates a short distance (by reason of the weight or power on the rack) and partially rotates the cam-wheel until the support for the pin *d'* is removed, when the pawl *d* drops and engages with the pinion.

The cam-wheel may be otherwise shaped, and in some instances it takes the form of a star or ratchet wheel arranged to act upon a projection on the end of the pawl, (or upon the end of the pawl itself,) so as to lift the pawl out of gear with the pinion. The cam, star, or other wheel *e* is free to rotate independently of the pinion *b* a distance equal to one or more teeth of the pinion; but the socket for the key or means for operating in both pinion and disengaging wheel is preferably arranged to coincide sufficiently, as shown on the drawings, (but may be otherwise formed,) so that the key may be readily inserted, yet allowing for the necessary independent motion of the one relatively to the other.

55 Figs. 4, 5, 6, and 7 illustrate another arrangement of the pawl whereby the cam-

wheel is dispensed with. The case *c* is shown, Figs. 4 and 5, of a special design to accommodate the working parts and in such a manner that the case itself forms the bearing for the pinion *b*. The part *c'* is for the rack, *c²* is for the pawl *d*, and *c³* for the pinion *b*, which is formed to approximately fit the recess *c³* provided for it. In this device the pawl *d* is situated at the back of the pinion *b* and is fulcrumed at *d²* in the case, a suitable spring, such as that shown, being provided. The pawl is formed with projections *d³*, adapted to engage with the teeth of the pinion *b* or with teeth or projections on the back face thereof. To operate the pinion either way, it is necessary to first disengage the pawl *d* by pressing the key or the like through the socket in the pinion, as illustrated by Fig. 7, *g* representing the key. 15 This action forces back the pawl, whereby a rotary motion of the pinion is permitted. In Figs. 8, 9, and 10 a somewhat similar arrangement is shown, the pressure of the key or the like (or of a flange or projection movable thereupon) causing the pawl *d* to become disengaged. *h* is a slotted plate or lever fulcrumed in the case *c* at *d²*, the upper end being formed with a wedge-piece *h'*, arranged to impinge upon the corresponding wedge projection *d'*, 20 integral with the pawl *d*. It will be seen that when the plate or lever *h* is pressed toward the pinion the wedge-pieces *h' d'* engage and cause the pawl to lift out of gear with the pinion. The case is formed to accommodate the working parts, as described with reference to Figs. 4 to 7 and with suitable modifications. 35

Fig. 11 is a modification in which the projection *d'* on the pawl *d* is extended downward beside the pinion *b* to form a finger arranged to be acted upon by a conical flange integral with or movable upon the key or the like, whereby the pawl is lifted out of gear when the key (or the movable conical flange) 40 is pressed inward.

Figs. 12, 13, and 14 illustrate the application of a double crown-toothed disk *i* to the pinion *b* instead of the pawl *d*. The pinion has teeth *m* formed thereon, engaging with 45 teeth *m'* on the crown-disk *i*. These teeth are sufficiently deep to insure their engagement at all times, so that the disk *i* and the pinion *b* always revolve together. The disk *i* is also formed with teeth *i'*, adapted to engage with teeth *i²*, cast or otherwise formed on the case, the teeth *i' i²* being shallow, and thus render the disk *i* capable of being disengaged from the teeth *i²* on the case when operated by a key or winder or the like. *k* is a spring 50 for pressing apart the pinion *b* and the disk *i*, whereby the whole is interlocked with the case, as in a clutch action.

To operate the mechanism, it is only necessary to insert the key or winder or the like and press the same, when the flange of the 55 key or the like forces back the disk onto the pinion, thereby disengaging the teeth *i'* from the teeth *i²* and permitting the pinion and disk to revolve. On removing the key or the pressure therefrom the spring *k* instantly 60 drives the disk *i* and pinion *b* apart, causing the whole to again become locked with the case.

The shape of the teeth *i' i² m m'* may be varied as preferred, ratchet-teeth being sometimes employed instead of those illustrated. 75 Similarly the teeth *m m'* may be dispensed with and other sliding connections (such as pins and sockets) may be used instead thereof.

The arrangements illustrated in Figs. 6 to 80 10 may be further modified by arranging the pinion to slide so as to engage with teeth on the case when in its normal position of rest (instead of the pawl, Figs. 6 and 7) to carry a conical flange adapted to engage with and 85 lift the pawl, (in place of the plate or lever *h*, Figs. 8, 9, and 10.) Also the crown-disk *i* may be placed at the back of the pinion and arranged to be always in contact with the teeth of the case, but capable of disengaging from 90 those on the back of the pinion by the application of pressure to the key, winder, or the like. Suitable springs are fitted where necessary to effect the proper working of the mechanism.

The cases may be provided with flanges or other means for attachment suitable to the purpose for which the regulator is required.

The pinion may be mounted on a shaft and the disengaging gear operated by a key, 100 winder, or other suitable instrument separately or in combination with cords and pulleys or other gear.

The key for hand use is sometimes provided with a flange or one or more pins capable of 105 being moved on the key-shaft by exterior means fitted to the handle.

I claim—

1. The combination of a pinion, a pawl normally in engagement therewith, and means 110 directly applied to said pinion for operating the same and releasing the pawl.

2. A pinion, means normally in engagement therewith to prevent the rotation thereof, and means directly applied to said pinion for simultaneously operating the same and releasing the means to prevent rotation.

In testimony whereof I have hereunto set my hand in presence of two subscribing witnesses.

ROBERT ADAMS.
